UNITED STATES PATENT OFFICE.

CLAIR DENNISON LAKE, OF BINGHAMTON, NEW YORK, ASSIGNOR TO THE TABULATING MACHINE COMPANY, A CORPORATION OF NEW JERSEY.

ATTACHMENT FOR CARD-SORTING MACHINES.

1,372,964.

Specification of Letters Patent. Patented Mar. 29, 1921.

Application filed August 24, 1920. Serial No. 405,613.

To all whom it may concern:

Be it known that I, CLAIR D. LAKE, a citizen of the United States, residing at Binghamton, in the county of Broome and 5 State of New York; have invented certain new and useful Improvements in Attachments for Card-Sorting Machines, of which the following is a full, clear, and exact description.

10 The invention upon which this application for Letters Patent is based resides in an attachment to the well known sorting machines for tabulator cards, such as are used in the Hollerith system. Such sorting machines do not form any part of the 15 present invention, but are or may be of the general character set forth in the Patent to H. Hollerith, No. 1,237,646, dated Aug. 21, 1917, and, in general terms are characterized by the following peculiarities.

A bunch of cards, which are to be sorted according to certain index holes punched therein, are successively brought into operative or control position, and set by means 25 of the record which they contain, devices which determine the point of delivery of each card, which devices remain so set while the cards are in transit to the sorting stations, where their delivery into appropriate 30 compartments is effected through the instrumentality of means controlled by such set devices.

The cards used in this system have a certain fixed number of columns in which the 35 index holes are punched, and this number is limited by practical conditions and considerations so that generally not more than 45 columns are permissible. The sorting machines when set and adapted for use operate upon a single column at a time, so that 40 under ordinary conditions it is permissible to punch but a single hole in a given column.

It follows, however, from the possible number of figures or positions in each column 45 for index holes, that the full capacity of the cards is seldom utilized, and it is manifest that if more than one index hole could be punched in a given column the possibility of sorting the cards according to the data 50 required would thereby be greatly increased.

It may also be desired to sort out from a mass of cards all having index holes above a certain point; for example, if each column be designed for ten index points, all cards 55 that are known to be punched above and

down to the fifth point may be sorted out and the others bunched.

These considerations make it desirable that the sorting machine be equipped with some device that will accomplish the desired results. Heretofore, special and separate cams, contacts and switches have been added and used for the purpose but the purpose of my present invention is to use a standard construction of the sorting machine throughout, but to employ in connection therewith an attachment which can be set at the will of the operator either for straight sorting or for splitting the column at any desired point, so that only those cards 60 which have holes above a certain position will be sorted and all others bunched and rejected. This device is known now in the art as a universal split for card sorting machines.

In the accompanying drawings I have illustrated the device which I have devised for this purpose, and which constitutes an attachment to a card-sorting machine of the nature hereinabove set forth.

Figure 1 is a view of the improved attachment in side elevation the side plate being removed to show the interior mechanism.

Fig. 2 is a top plan view with the cover removed.

Fig. 3 is a view in front elevation, the cover being removed.

Fig. 4 is a view in side elevation of a ratchet and pawl together with the set 90 wheel.

Fig. 5 is a sectional view along the drive shaft.

Fig. 6 is a sectional view through the latch mechanism and tripping cam.

Fig. 7 is a section showing a reset mechanism.

Fig. 8 is a detail of a cam and lever.

Fig. 9 is a rear view of a latch lever, and

Fig. 10 is a wiring diagram of the apparatus.

The operative parts are contained in a casing 1, which is set upon the frame of a sorting machine in such position that it may be driven by the sorting machine 105 through gear wheels 2, and make one complete revolution or cycle for each card that passes through the sorter. This rotary movement is imparted to a shaft 3 which carries two cams 4 and 5, and these cams 110

operate contacts 6 and 7 in the manner hereinafter described and these contacts are properly secured to or supported by the frame of the device.

5 The purpose of the contacts 6 and 7 will be understood from the diagram Fig. 10. In this figure 8 is a contact brush in the sorting machine and the cards to be sorted are passed between it and a roller or metal 10 plate 9, so that when a perforation in the card comes under the brush the current from a suitable source 10 flows through the contacts and the sorting magnet 11, and by the latter is delivered into its appropriate 15 compartment or receptacle.

The cam 4 is so formed as shown in Fig. 1, that it raises the contact 6 only for a brief period at the end of each revolution or cycle; at all other times the circuit, which 20 is completed by the contact coming into engagement with a stop 12, is open.

The contact 7 is flexibly connected with the frame at 13 and completes its circuit when it engages a fixed stop 14 on a rigid 25 bar 15. It is normally locked up against the force of its spring by a stop 16 which it carries engaging with a latch on the lever 17 (Figs. 6 and 7). The cam 5 is shaped to engage the tail of lever 17 during a given 30 part of its rotation and thereby throws the latch and releases the contact 7, allowing it to complete its circuit.

The connection, therefore, between the brush 8 and the sorting magnet 11 cannot 35 be made except at the end of a cycle through contact 6, unless the latch has been tripped and contact 7 allowed to drop.

The cam 5 has a single projection. It is secured by set screws to a hub 18 which is 40 mounted free to turn on the shaft 3. It is adapted, however, to be rotated by a pawl 19, Fig. 4, which engages with a ratchet wheel 20 fast or keyed to shaft 3.

The hub 18 has a flange, the periphery of 45 which is provided with gear teeth 21 and to this flange by screws 23 is secured an index wheel 22. In the frame of the device and mounted parallel with the shaft 3 is a shaft 24 which carries a sleeve 25 with an 50 arm in which is set a toothed thumb wheel 26. Rigid with said shaft 24 is an arm or lever 27, Figs. 2 and 8, with a button 28 at its end and having a projection 29 thereon. If this lever be depressed and the shaft 3

55 turned by hand until a notch 30 in a disk 31 fixed to the shaft comes under the projection 29, then the thumb wheel 26 will be brought into gear with the teeth on the flanged hub 18, and by turning the thumb 60 wheel, the index wheel will be set to expose any desired number at the zero or registering point. This means that the cam 5 will be set so that its high point will trip the latch 17 at any given point in the cycle 65 which is represented by the figure on the

wheel 22 at the zero point, and as the figures on this wheel correspond with the horizontal rows of numbers on the card, or to the numbers which may be punched out from such card, it follows that the machine may 70 thus be set to sort all cards having holes beyond such point, but none below it.

For example, if a column is to be split between 5 and 6 the index wheel is turned to expose 5 which will so adjust the cam 5 75 that no hole punched in a number greater than 5 will have any effect on the operation of the machine. It will be understood that the positions for the holes are numbered consecutively from the top of the card downward, and that the cards move over the brush downward.

When the device has thus been set it may be operated indefinitely to sort all cards punched in that part of a column determined by the adjustment, but by each rotation of the shaft 3 the latch is not only released but locked. The latter function is performed by a cam 32 on which rides a roller 33 on a pivoted lever 34, having a 80 spring 35 connecting it to the frame. When the lever is raised by the cam a pin 36 thereon engages a part of the contact 7 and raises the same until its stud 16 reengages with the pivoted and spring actuated latch 95 17. This operation is performed near the end of each cycle.

With reference to Fig. 10: The operation of these sorting machines is well and widely known and in this application requires no 100 further explanation. The circuit controller 6 may be disregarded but its purpose is to close a circuit from the brush to the sorting magnet for a brief interval near the end of the cycle, and immediately after the circuit 105 through contact 7 has been broken. This is a feature not new in this connection and is intended to give ample time and opportunity for the operation of the machine when the brush is passing over the last 110 horizontal line of holes or index points on a card.

This device may be attached to any card sorting machine without change or modification of the latter. It forms a highly useful and efficient means of utilizing to greater advantage the possibilities of the cards and apparatus as heretofore constructed.

What I claim is:—

1. A universal split attachment for card sorting machines, comprising, in combination, a circuit controller in the path of the circuit which includes the brush contact and a sorting magnet, and means for closing the same by the operator of the machine at any 125 predetermined part of the cycle of operation.

2. A universal split attachment for card sorting machines, comprising, in combination, a circuit controller in the path of the 130

circuit which includes the brush contact and a sorting magnet, and an adjustable cam for closing said controller at any predetermined point in the cycle of operation.

5 3. A universal split attachment for card sorting machines, comprising, in combination, a circuit controller normally locked out of operation, and means for unlocking the same at any predetermined point in each 10 cycle of operation and thereby permitting it to close a break in the circuit to a sorting magnet.

4. The combination with the card sorting circuit of a card sorting machine, of a circuit controller therein, means for normally locking the same in inoperative condition, 15 an adjustable cam which, by its adjustment, operates to unlock said circuit controller at

any predetermined point in the cycle of operation and permit it to operate, and means 20 for relocking said controller in inoperative condition at the end of the cycle.

5. The combination with the card sorting circuit of a card sorting machine, of a circuit controller therein, means for normally 25 locking the same in inoperative condition, a cam, an index wheel and means for setting the latter to adjust the cam to unlock the circuit controller at any predetermined point on the cycle of operation and permit 30 it to operate, and a second cam adapted to engage with said controller and relock the same at the end of each cycle.

In testimony whereof I hereto affix my signature.

CLAIR DENNISON LAKE.
